(57) CLAIM

The ornamental design for a tin can lid opener, as shown and described.

DESCRIPTION

FIG. 1 is a perspective view of a tin can lid opener showing my new design;

FIG. 2 is a side elevational view of FIG. 1;

FIG. 3 is a bottom plan view of FIG. 1;

FIG. 4 is a side elevational view of the tip portion shown separately for ease of illustration; and,
FIG. 5 is a top plan view of FIG. 1.

The broken lines shown in Fig. 1 are for illustrative purposes only and form no part of the claimed design. The shank of the tin can opener is shown broken away to indicate indeterminate length.
